UNITED STATES PATENT OFFICE.

WARREN D. HUSE, OF LACONIA, NEW HAMPSHIRE.

CIRCULAR-KNITTING MACHINE.

SPECIFICATION forming part of Letters Patent No. 239,168, dated March 22, 1881.

Application filed November 13, 1879.

To all whom it may concern:

Be it known that I, WARREN D. HUSE, of Laconia, in the county of Belknap and State of New Hampshire, have invented an Improved 5 Circular-Knitting Machine; and I do hereby declare that the following is a full and exact description thereof, reference being had to the accompanying drawings, making part of this specification.

10 Figure 1 is a front elevation of a circular-knitting machine provided with my improvements; Fig. 2, a partial side view of the same, taken at right angles to the view in Fig. 1; Fig. 3, a top view of the same.

15 Like letters designate corresponding parts in all of the figures.

My improvements are especially applicable to knitting-machines with two sets of needles for knitting ribbed work, the improvements 20 automatically supplying single threads of different colors thereto, and determining the style or pattern of work in colors by mechanism constructed to be readily changeable to different patterns. The improved devices for this purpose are substantially as hereinafter specified.

In the drawings, A represents the revolving dial-plate of a circular-knitting machine, carrying one set of needles, a a, and B the needle-cylinder, carrying the other set of needles, b b, 30 for knitting ribbed work. C is the revolving ring, carrying two thread-guides, D E, each being supplied with a different color of thread. These thread-guides are respectively mounted on swinging arms G H, which are pivoted on a pin, e, so as to swing radially toward and from the center of the machine. Each thread-guide is a short tube or eye, first made separate and then soldered or otherwise removably secured to its arm, so that when one is worn out it can 35 readily be replaced by a new one. The thread-guides are alternately placed in position, one outward to deliver the thread to the needles and the other inward back of the needles, so that its thread will not be taken by the needles.

40 For alternately shifting these thread-guides to these respective positions I couple to them respectively two vibratory levers, I J, pivoted at d to a support carried by the revolving ring C, and each carrying at its lower end 45 a stud or pin, e, arranged to ride over cam-projections f f on a vertical-faced cam-disk, K,

which revolves on a radial pivot, g, carried by the revolving ring C. These cam-projections are so spaced that when the stud e of one lever rides upon one of the projections the other stud is in a space between two projections, and the levers I J are so arranged that when a stud is moved forward by a cam-projection, f, the thread-guide moved thereby is carried inward to throw its thread out of the work, and when the stud is moved back into a space between two cam-projections the corresponding thread-guide is moved outward to bring its thread to the work. The backward movement of the levers I J is effected by counter-springs h h. 55 This cam-disk is automatically moved by a device which, with some additions, is substantially the same as employed by me for alternately bringing to the surface of knit-work different-colored threads for double-thread 60 knitting, as fully described in Letters Patent No. 220,924, granted to me on the 28th day of October, 1879. I will therefore describe it here as used for moving the thread-guides in the present machine.

75 From the periphery of the cam-disk K project cogs or teeth i i, twice as many as there are cam-projections f f on the face of the disk, and at regular distances apart, so that on moving the disk around a distance equal to the 80 space between the centers of two adjacent cogs the positions of the two thread-guides will be reversed, as will be readily understood. To move the disk such a distance at one revolution of the knitting-machine, a rod, L, is projected up through a ledge, M, of the machine-frame far enough to strike one of the cogs i i on the cam-disk, the lowest in position each time, and thus, whenever this rod is projected upward into the proper position, as shown in 85 Fig. 1, the cam-disk is moved the distance of one cog every time it comes round to this rod; but when the rod is lowered out of the way the knitting goes on without change of thread. The rod L is pivoted at its lower end to a horizontal lever, N, pivoted at j to the frame of the machine. This lever has a stud, k, on its under side, which, when it rides in its lowest position, allows the rod L to sink out of the way of the cogs on the cam-disk K; but by 90 causing the stud to ride upon a suitable projection the rod is raised and brought into the 95 100

pathway of the lowest cog on the cam-disk. This stud may ride on the periphery of a cam-wheel, as described in the aforesaid Letters Patent; but I prefer to use a sprocket-disk, O, attached to the face of the ratchet-wheel Q, instead, and mount a pattern-chain, P, thereon, the links *ll* of the chain fitting over sprocket-projections *mm* on the said disk. This enables me to use pattern-chains with various spurs *nn* thereon for the stud *k* to ride upon, these chains being cheaply made, of various combinations of links, and very quickly changed, as I make them large enough to fit loosely around the sprocket-disk, as indicated in Fig. 1, so as to be put on and off in a moment. This also allows me to knit stocking-legs of any desired length, and another advantage is secured by the use of these chains on a sprocket-disk, since it enables me to adjust the position of the links of the chain by adjusting the disk upon the ratchet-wheel Q, to which it is attached. Thus a slot, *o*, in the disk and tightening-screw *p*, as shown, effect this purpose.

The ratchet-wheel Q is intended to be moved one tooth at each revolution of the knitting-machine, so that the positions of the figure or change of color of thread are readily effected. This is effected by a device, as shown, similar to that employed in the said Letters Patent. Thus a set of cogs on the lower edge of the revolving ring C gears into a cog-wheel, R, and a smaller wheel, S, on the same shaft turns a cog-wheel, T, on the shaft of which is an eccentric, V, which vibrates a counterweighted lever, W, which carries the pawl *q* that operates the said ratchet-wheel.

The cam-disk K is held in position after each movement thereof by the rod L, by means of a friction-spring, *r*, Fig. 2, bearing against its rear surface.

As the thread-guide either carries its thread in or out of the work the thread is automatically caught by a catch-lever, X, operating as follows: It is pivoted at *s* to a holder on the revolving ring C, and its upper end is pressed against the edge of a plate, Y, secured to the shaft of the dial-plate and revolving ring. This pressure is produced by some spring *t*, and is sufficient to hold the thread thrown out of the work securely. The catch-lever is opened or swung back from the plate Y to let one thread out and the other thread in at each change by means as follows: This catch-lever has on its lower end a cam, *u*, so formed and arranged that directly after the cam-disk is moved by the rod L to shift the thread-guides this cam also, in turn, strikes the rod L, which

presses the lower end of the catch-lever inward and the upper end outward or open. 60 The spring *t* again closes the catch-lever as soon as its cam passes by the said rod. Of course, when the rod is dropped to not operate the cam-disk it does not operate the catch-lever. 65

To insure the retention of the thread each time it is caught by the catch-lever, a gage, stop, or guide, *v*, projects outward over the catch-lever from the top of the plate Y, as shown. This prevents the thread from accidentally passing beyond the catch-lever. The thread, having been caught by the catch-lever, is held from paying out, and as the thread-guide and catch-lever continue to pass round the thread is broken off near the work, and the other 75 thread alone continues the knitting, the end of the severed thread still being held securely by the catch-lever, ready to be brought into the work again at the next shifting of the thread-guides. The loose end of the broken thread 80 on the work is directly swept smoothly down to the web, so as to show little or not at all in the web. This is effected by means of a brush, Z, of wire or other sufficiently stiff material, on a holder, *w*, attached to the revolving ring 85 C. The position of this brush is clearly shown in the drawings.

It is to be understood that the threads used in the knitting are wound on bobbins carried on the yoke *z*, attached to the revolving ring 90 C in the usual manner.

What I claim as my invention, and desire to secure by Letters Patent, is—

1. The combination of the cam-plate Y, catch-lever X, provided with a cam, *u*, and rod L, 95 substantially as and for the purpose herein specified.

2. The combination of the gage-stop *v*, cam-plate Y, catch-lever X, provided with a spring, *t*, and cam *u*, and the rod L, substantially as 100 and for the purpose herein specified.

3. The combination of the catch-lever X, provided with a spring, *t*, and cam *u*, the cam-plate Y, rod L, cam-disk K, levers I J, and thread-guides D E, substantially as and for 105 the purpose herein specified.

4. The combination of the brush Z and holder *w* with the revolving ring C of a circular-knitting machine, substantially as and for the purpose herein specified. 110

The foregoing specification signed by me this 13th day of October, 1879.

WARREN D. HUSE.
